UNITED STATES PATENT OFFICE

2,612,373

GOLF TEE

Maurice Campbell Pierce, Madison, Wis.

Application August 22, 1946, Serial No. 692,183

3 Claims. (Cl. 273—33)

1

My present invention, as is clearly shown in the accompanying descriptions and drawings, pertains to novel golf tees adapted for ready attachment to the shafts of golf clubs or the rims of golf bags, whereby improved devices in this category are provided to the golfer as a convenience to obviate the awkward necessity of storing and carrying them in pockets or special holders.

The prevalent practice of carrying golf clubs and tees separately has many disadvantages as compared to their attached storage. A few of such disadvantages are enumerated as follows: (1) Carrying inconvenience, (2) damage to wearing apparel, (3) dirt transported into pockets, (4) injury to player's body and hands, (5) unnecessary delay.

Golf tees now in use have one or more of the following limitations for convenient and ready use:

1. They are not designed or intended for attachment and carriage by self-gripping engagement with the shaft of a golf club or the rim of a golf bag.
2. They are formed for storage in pockets or special accessory holders which in the case of women players are not always available when wanted.
3. The carrying of tees in the player's pocket may result in tearing the same or injury to the player's body and also is unsanitary.
4. Much time is wasted in removing tees from pockets especially if they become caught on other articles therein or the player's hands are gloved or sticky with perspiration or stiff from cold.

5. Prevailing tees, whether preformed or intended for shaping from blanks are limited and suitable for placement either on the surface of the ground on the one hand or for anchoring in the ground on the other. The peg tee, for instance, cannot be thrust sufficiently deep in hard ground to properly support the ball nor is it effective in muddy or sandy ground. The presently used surface tees without anchoring projections will not balance on thick springy sod and they are not intended or suitable for anchorage in hard ground lying beneath the sod.

One object of this invention is to provide golf tees which are not hampered with the above named and other limitations; tees of great convenience and versatile utility, designed to saddle readily, clasp snugly and release quickly at will over the shafts of standard golf clubs or the rims of customary golf bags with the use of one hand alone.

2

Another object of the invention is to eliminate the necessity for various holders and devices for storing tees by providing a self-attaching tee.

A further object of the invention is to provide a golf tee suitable for securely supporting a golf ball at the desired intermediate elevations above the surface of the footing, existing on the tee stations; tees that will balance under the weight of a ball on hard, uneven, bald surfaces or on soft sand or mud; tees that are at the same time designed and suitable for thrusting in the ground that lies beneath thick grass or other springy vegetation.

Secondary objects are as follows:

15 To provide means whereby the smallest possible and most accessible space is occupied in the storage and carrying of tees, combined with utmost readiness for speedy action, simplicity, reliability, light weight, lack of resistance to follow-through of driver stroke, safety from injury to body and clothes, cleanliness, quick placement and retrieval of tee, with consequent speeding up of other flight groups and better revenues for golf courses.

20 With the above and other objects in view, which will appear as the description proceeds, the invention resides in novel construction, combination and arrangement of parts substantially as hereinafter described and more particularly defined by the appended claims, it being understood that such changes in the precise embodiment of the herein described invention may be made as come within the scope of the claims.

25 In the accompanying drawings are several illustrations of the physical embodiment of the present invention, constructed according to the best mode so far devised for the practical application of the principles thereof.

30 Figure 1 shows two tapered tees, comprised of 40 gapped or longitudinally slotted sleeves or tubes of suitable diameter, resilient or expandible and contractible material, the lower unit clasped about the wound joining of the head and shaft of a golf club 2. The body of the tee 1 has cut 45 away segments 4 to effect ground contact points or tapered projections or anchoring feet 5. The gap or slot 6 coincides with the deepest cut point of one of the cut away spaces so that the lower end of said slot has a flaring mouth which is 50 of material assistance in the placement of the tee in its carrying position.

35 In Fig. 1 the upper tee is pictured in the process of attachment or removal onto the shaft 3, being facilitated by the widened gap 6 since the 55 flaring mouth at the bottom edge of the slot 6 is

the first part to be pressed against the shaft 3 thereby expanding the sleeve or tube so that its slot 6 is opened up sufficiently for the tee to engage over the shaft and then contract about the same through substantially its entire length.

Figure 2 represents the tapered tee with side walls 1, cut away spaces 4, ground contact points 5 and gap 6. The tee rests lightly on the playing surface preparatory to perching a golf ball.

Figure 3 illustrates the tapered tee thrust slightly downward into the ground to lower the ball seat, while the diameter is increased by widening the gap. A golf ball 8 is supported in playing position.

Figure 4 shows the gapped or longitudinally slotted sleeve or tube with untapered side walls 1, contact points 5, cut out spaces 4, and gap or slot 6. It has been slid onto the lower portion of a golf club hand grip 7. The tee for hand grip attachment is naturally of somewhat greater diameter than one intended to fit the lower part of the shaft.

Figure 5 is the untapered tee of greater diameter placed upright in ball supporting position.

Figure 6 shows two untapered tees, the unit at the left in process of detachment from the upper extremity of a golf club hand grip 7. This procedure is facilitated by means of the cut away spaces 4 and the gap 6. The tee unit at the extreme right in Figure 6 is clasped about the upper end of the hand grip for convenient storage and carrying.

I claim:

1. As a new article of manufacture, a golf tee comprising a hollow substantially tubular resilient member having a wide lengthwise extending slot permitting considerable contraction and further expansion of its circumference to provide varying circumferential areas on which to support a golf ball at varying heights from the ground and provided with ground piercing teeth to hold the tee in the desired circumferentially adjusted position.

2. As a new article of manufacture, a golf tee for self-gripping engagement with rounded portions of golf equipment such as the shaft of a golf club or the rounded rim of a golf bag comprising a hollow substantially tubular resilient member, of contractible and expandible varying diameters and having a slot extending lengthwise thereof and of an initial diameter to snugly engage, throughout substantially its entire length,

with said rounded portion, said slot having a flaring opening at one end to facilitate expansion of said tee over the rounded portion as it is pressed against the same, said tee after the separation of its slotted sides by said rounded portion contracting into gripping engagement with said rounded portion and having a ground piercing tooth in which the flaring of the slot at the base of the tee forms a side of said tooth.

3. As a new article of manufacture, a golf tee for self-gripping engagement with rounded portions of golf equipment such as the shaft of a golf club or the rounded rim of a golf bag comprising a hollow substantially tubular resilient member, of contractible and expandible varying diameters and having a slot extending lengthwise thereof and of an initial diameter to snugly engage throughout substantially its entire length, with said rounded portion, said slot having a flaring opening at one end to facilitate expansion of said tee over the rounded portion as it is pressed against the same, said tee after the separation of its slotted sides by said rounded portion contracting into gripping engagement with said rounded portion and having ground piercing teeth in which the flaring of the slot at the base of the tee forms the sides of spaced ground piercing teeth and the side of the tee opposite to the slot at the base is provided with a recess aligned with the flared portion of the slot to further facilitate expansion of said tee over said rounded portion.
